CLAIM

The ornamental design for a mounting boss, as shown and described.

DESCRIPTION

FIG. 1 is a top front perspective view of my present invention.

FIG. 2 is a rear bottom perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The dash-dot-dash lines in FIGS. 2, 3 and 8 define the boundary tracking the bottom profile inside of which no claim is made. The dotted lines in FIGS. 1-8 depict features of the mounting boss to which no claim is made.
